UNITED STATES PATENT OFFICE

HORACE MILTON CROCKETT, OF LAWRENCE, MASSACHUSETTS.

SLIPPER-HANGER.

SPECIFICATION forming part of Letters Patent No. 352,738, dated November 16, 1886.

Application filed December 21, 1885. Serial No. 186,395. (No model.)

To all whom it may concern:

Be it known that I, HORACE MILTON CROCKETT, of Lawrence, in the county of Essex, of the Commonwealth of Massachusetts, have invented a new and useful Improvement in Slipper-Hangers; and I do hereby declare the same to be described in the following specification, and represented in the accompanying drawings, of which—

10 Figure 1 is a top view, Fig. 2 a front elevation, and Fig. 3 a perspective view, of a slipper-hanger of my invention, the nature of which is defined in the claims hereinafter presented.

15 It is constructed of a single piece of wire, bent first at its middle in the form of an eye, *a*. Next each part projecting from the loop is bent or curved in a semicircle or bow, *b*, in a plane at a right angle to that of the eye. 20 Next the two parts *c*, beyond the bends *b*, are turned upward toward each other in the plane of the said eye, and are riveted or soldered together at their ends, so as to form an eye, *d*.

When the article is used, it is to be hung 25 upon a hook or a screw or nail, inserted in a wall or side of a room, or in the door of a wardrobe, for instance, and is to be held in place by a screw inserted through the eye and into such wall, or door, or side of a room. To finish the hanger it may be covered with cloth or upholstered in any proper or desirable manner. It is intended for holding a pair of shoes 30 or slippers inserted in the bows *b*.

A guard, to prevent the slippers from falling out of the hanger, may be extended across 35 it directly in rear of its bends *b*, such guard being a piece of wire, *d'*, secured at its ends to the outer extremities of the two bows.

I claim—

1. As a new or improved article of manufacture for use as set forth, the slipper-hanger, substantially as described, composed of a piece of wire bent at its middle to form in it the eye *a*, and thence in opposite directions in a plane at a right angle to that of the eye to form in it 45 the two semicircles or bends *b*, and thence upward in the plane of the eye, and having its parts *c* so bent upward inclined toward each other and united at their ends, all being essentially as represented. 50

2. The combination of the wire or guard *d'* with the slipper-hanger, substantially as described, composed of a piece of wire bent at its middle to form in it the eye *a*, and thence in opposite directions in a plane at a right angle to that of the eye to form in it the two 55 semicircles or bends *b*, and thence upward in the plane of the eye, and having its parts *c* so bent upward inclined toward each other and united at their ends, all being essentially as represented.

HORACE MILTON CROCKETT.
